CONDENSER

Charles B. Tuley, Glenolden, and John W. McNulty, Ridley Park, Pa., assignors to Westinghouse Electric & Manufacturing Company, East Pittsburgh, Pa., a corporation of Pennsylvania

Application April 6, 1938, Serial No. 200,344

3 Claims. (Cl. 257—43)

Our invention relates to surface condensers of the multiple-pass type and it has for an object to provide apparatus of this character wherein the tubes of the respective passes are disposed in such manner that the tubes of the first pass are more widely spaced than the tubes of the second or subsequent passes.

It has been customary, in laying out tube sheets for two or multiple pass condensers, to pitch the tubes closer together in the first water pass than in the second or subsequent passes; however, because of the lower water temperature in the first pass, the latter has the greater condensing capacity. For example, with a two-pass condenser having substantially equal numbers of tubes in each pass, the first pass may have a capacity for condensation of the order of 60 to 65 percent of the total capacity of the condenser. In order that the passes may be arranged to accommodate steam in proportion to the capacities thereof, the tubes of the first pass should have greater spacing or pitch than the second and so on. Therefore, in accordance with our invention, we provide a condenser wherein the tubes of the first pass are spaced further apart or are more widely pitched than those of the subsequent pass, to provide greater flow area for the increased quantity of steam entering the first pass.

A further object of our invention is to provide a condenser of the multiple-pass type with the tubes of each pass directly exposed to entering steam and with the spacing or pitch of the tubes of the passes a maximum in the initial pass and a minimum in the final pass.

A further object of our invention is to provide a radial flow condenser having the tubes arranged in horizontally juxtaposed first and second passes of substantially equal arcuate extent and wherein the tubes of the first pass occupy a relatively larger cross-sectional area of the nest than those of the second pass so that the tubes of the first pass may be more widely spaced.

A further object of our invention is to provide a radial flow condenser having the tubes arranged in horizontally juxtaposed first and second passes of substantially equal arcuate extent and the group of tubes of the first pass being so arranged that a central portion protrudes reentrantly within the group of tubes of the second pass, thereby providing greater area for the first pass so that the tubes of the latter may be more widely spaced.

A further object of our invention is to provide a radial flow condenser with the tubes arranged

in horizontally juxtaposed first and second passes wherein the tubes of the first pass include a central group protruding within the group of tubes of the second pass so that the tubes of the first pass may be more widely spaced and so that a laterally symmetrical air offtake may be arranged within the confines of the tubes of the first and colder pass.

These and other objects are effected by our invention as will be apparent from the following description and claims taken in connection with the accompanying drawing, forming a part of this application, in which:

Fig. 1 is a transverse sectional view of a condenser embodying our invention;

Fig. 2 is an enlarged fragmentary view of the lower vertical portion of Fig. 1; and,

Fig. 3 is a diagrammatic plan view of the condenser of Fig. 1.

In the drawing, there is shown a condenser 10 comprised by a shell 11 provided with a steam inlet opening 12 at the top thereof, and having attached thereto at opposite ends water boxes 13 and 14. A partition 15 divides the waterbox 13 into inlet and outlet chambers 17 and 18, respectively. The chamber 17 is provided with an inlet connection 19 while the chamber 18 is provided with a corresponding outlet connection 21. A plurality of tubes 22 extend longitudinally of the shell from the waterbox 13 to the waterbox 14 whereby water entering the inlet chamber of the box 13 may flow through certain of the tubes 22 to the waterbox 14 where the flow is reversed and the water conveyed through the remaining tubes to the outlet chamber 18 of the water box 13.

The tubes 22 form a radial-flow tube nest 23 of substantially circular cross-section and are so disposed as to define, with respect to the shell, a steam space diminishing in cross sectional area from the steam inlet opening 12 at the top of the condenser to the bottom of the shell. By this arrangement, steam may freely enter the tube nest at all points around its periphery.

At the center of the tube nest 23, is an air offtake core 26, extending the entire length thereof. Exhaust pipes 28 and 29 conduct the air and non-condensable gases from the offtake to the exterior of the condenser, in a well known manner.

Steam, entering the condenser through the inlet opening 12 at the top thereof, passes radially among the tubes of the nest 23, and is condensed, air and non-condensable vapors passing into the offtake 26, the baffles 31 and 32 providing for dis-

tribution of steam in the nest. The lowermost portion of the shell has one or more openings 36 for conducting condensate to a suitable hotwell (not shown).

5 The tube nest 23, as herein illustrated, consists of a first pass 37 and a second pass 38. The first pass has a greater cross-sectional area than the second pass, as indicated by the dotted line showing of the partition 16 which divides the
10 waterbox 13 into inlet and outlet chambers.

Both passes are provided with approximately the same number of tubes of the same size; and, since the first pass has a greater cross-sectional area than the second pass, the tubes of the first pass are spaced farther apart than those of the second pass, as may be seen from Fig. 2. This construction provides more space for flow of steam between the tubes of the first pass than between those of the second pass.

20 While the passes are of equal peripheral extent, the wider spacing of the tubes of the first pass provides greater entrance area to accommodate the relatively greater quantity of steam which may be condensed by the first pass. Furthermore, if the greater cross-sectional area of the first pass to obtain the wider tube spacing is secured by having a portion of the tubes of the first pass protrude reentrantly into the tubes of the second pass, such protruding portion of 25 tubes is used to enclose the air offtake to advantage, not only for the reason that a symmetrical location of the air offtake is preserved, but for the further reason that such offtake is entirely surrounded by the relatively cooler tubes of the 30 first pass.

While we have shown herein a condenser having only two passes, it will be clear to those skilled in the art that the same principles of construction can be applied to condensers having a greater number of passes with equally advantageous results.

While we have shown our invention in but one form, it will be obvious to those skilled in the art that it is not so limited, but is susceptible of various changes and modifications without departing from the spirit thereof, and we desire, therefore, that only such limitations shall be placed thereupon as are imposed by the prior art or as are specifically set forth in the appended claims.

What we claim is:

1. In a condenser, a shell, a nest of tubes within the shell and defining a steam space with respect to the latter and the shell having an

exhaust steam admission opening communicating with the space, means providing an air off-take, and means cooperating with the tubes to provide for flow of water therethrough in a plurality of passes in succession, each pass having tubes directly exposed to said steam space so that steam flows from the latter in parallel through the passes toward the offtake and the tubes of the first pass being more widely spaced than those of the final pass.

2. In a condenser, a shell, a nest of tubes within the shell and defining a steam space with respect to the latter and the shell having an exhaust steam admission opening at the top thereof communicating with the space, means cooperating with the tubes to provide for flow of water therethrough in a plurality of passes in succession, and an air offtake, said passes being comprised by horizontally juxtaposed groups of tubes and the outermost tubes of each group being directly exposed to said steam space so that steam flows from the latter in parallel among the tubes of the passes toward the air offtake and said groups being of substantially equal arcuate extent with the tubes of the initial pass occupying a larger cross-sectional area than the tubes of the final pass and with the spacing of the tubes of the first pass greater than that of the final pass.

3. In a condenser, a shell, a nest of tubes 30
within the shell and defining, with respect to
the latter, a steam space which substantially en-
compasses the nest and the shell having an ex-
haust steam admission opening communicating
with the space, means cooperating with the tubes 35
to provide for flow of water therethrough in first
and second passes, the tubes of the passes being
arranged in horizontally juxtaposed groups of
substantially equal numbers of tubes and of
substantially equal peripheral extents, the tube 40
group of the first pass protruding reentrantly
into the tube group of the second pass, with the
cross-sectional area occupied by the first pass
larger than that of the second pass and with the
tubes of the first pass more widely spaced than 45
those of the second pass, and an air offtake en-
compassed by tubes of the first pass and ar-
ranged at the region of the protruding tubes
thereof, the outermost tubes of each pass being
directly exposed to said steam space so that
steam flows from the latter in parallel through
the passes toward the offtake. 50
